UNITED STATES PATENT OFFICE.

JAMES ALBERT PENGRA, OF KNOXVILLE BOROUGH, ALLEGHENY COUNTY, PENN.
SYLVANIA.

LOUD SPEAKER.

Application filed July 19, 1922. Serial No. 575,926.

To all whom it may concern:

Be it known that I, JAMES ALBERT PENGRA, citizen of the United States, and residing in the borough of Knoxville, in the county of Allegheny and State of Pennsylvania, have invented or discovered a new, useful, and Improved Loud Speaker, of which the following is a specification.

10 My invention consists in a new and improved "loud speaker" or amplifier for amplifying sounds, such as in connection with wireless telephone receiving sets.

15 More particularly, my improved loud speaker is designed for use in connection with the ordinary head set receiver, so that the sounds reproduced by the latter may be greatly amplified and may be heard by any number of people.

20 Generally speaking my improved loud speaker, which is preferably made of thin wood, is of the following construction. There is provided a larger central amplifying chamber expanding towards its emission end at the front of the instrument. There 25 are further provided a pair of smaller amplifying chambers which may be conveniently disposed one on each side of the larger chamber and expanding in a direction opposed to the expansion of the central chamber. The larger ends of the second 30 named chambers are in communication with the smaller end of the first named chamber by means of open ports of substantially the full capacity of the smaller chamber. When 35 my amplifier is to be used as a loud speaker for wireless telephone sets the smaller end of each of the second named chambers is connected to a tube whose other end is provided with a suitable orifice with which is 40 registered the emission opening of one of the ear pieces of the receiving head set, suitable means being provided for maintaining such registration. Said tubes preferably expand towards their connection 45 with the second named chambers and the connecting ports or orifices are preferably of substantially equal capacity with the smaller ends of said chambers.

50 Other novel features of construction and arrangement of parts will appear from the following description.

In the accompanying drawings which illustrate a practical embodiment of the

principles of my invention, Fig. 1 is a side elevation of the loud speaker; Fig. 2 is a 55 plan view of the same; Fig. 3 is a horizontal section taken along the line III—III in Fig. 1, and Fig. 4 is a front elevation of the same.

The following is a detailed description of 60 the drawings.

A represents the larger and central amplifying chamber, having its larger and sound emitting end at the front of the instrument. The walls of said chamber are 65 preferably formed of thin wood, and may be of a single thickness or laminated as may be preferred. The top wall 1 of said chamber preferably inclines downwardly towards the rear while its bottom wall 2 inclines upwardly towards the rear and its side walls 3 incline inwardly towards the rear. The rear end of the chamber A is closed by the vertical wall 4 and said wall is preferably extended downwardly to form the support or leg 5. The wall 4 is also preferably extended laterally to form the closure for the rear ends of the smaller amplifying chambers B.

At either side of the larger chamber A 80 is positioned one of the two smaller amplifying chambers B. The side walls 3 of the larger chamber forming the inner side walls of said chambers B. The said chambers B are completed by top walls 6, bottom walls 85 7, outer side walls 8, front end walls 9 and the said rear wall 4. The chambers B expand rearwardly, thus in a direction the reverse of the expansion of the central chamber A. The rear end of each of the 90 said chambers B is in communication with the rear end of the central chamber A by an open port 10 in the intervening wall 3, said ports being of substantial equal capacity with the larger ends of the chambers B.

C represents a pair of tubes which may be of metal such as brass, or may, if desired, be built up of wood or other suitable composition. These tubes are preferably tapered and their larger ends are in communication with the smaller ends of the side chambers B and are preferably of substantially equal capacity therewith. The smaller ends of said tubes are intended to be placed 105 in registration with the sound emission ori-

fices of the ear pieces of an ordinary wireless telephone receiver head set.

In the preferred form of my device the tubes C are contained within the chamber A, thus adding to the compactness and appearance of the instrument. Thus ports 11 in the side walls 3 lead into the smaller or front ends of the chambers B, and the larger ends of said tubes C are connected to said ports 11. The tubes C extend rearwardly in the upper portion of the chamber A and near the rear end of the latter turn upwardly and connect with a pair of transversely aligned orifices 12 in the top wall 1.

When the loud speaker is in use the ear pieces D of a receiver head set, indicated by dotted lines in Fig. 2, are placed on the top wall 1 with their emission openings turned downwardly and in registration with the orifices 12 in said wall. To properly spot the ear pieces in position, I prefer to provide a bent metal guard member E fixed on the wall 1 and provided with a pair of undercut and curved socket portions 13 which are engaged by the ear pieces E as indicated in Fig. 2. I also prefer to provide a clamping bar 14 pivotally mounted on a vertical post 15 and having resilient ends which may be sprung over the ear pieces D to hold the same firmly in proper position.

It is quite evident that the sound emitted from the ear pieces E will travel along the tubes C and thence through the said chambers B and thence through the central chamber A. The sounds are thus greatly amplified and are given a very clear, pure tone devoid of all harshness and metallic sounds so characteristic of many of the amplifiers now in use. The result obtained is similar but superior to the results obtained by the use of the amplifying horn of a phonograph for the same purpose. However owing to the fact that I obtain in a very small compass a relatively great "horn" or amplifying length, I am able to obtain a greater amplification of the sound than is possible by the use of a phonograph horn. The sound passages leading from the ear pieces to the central amplifying chamber expand for their full length and such expansion is continued through the central chamber to the emission opening.

In addition to the above named advantages my improved loud speaker is applicable to the ordinary head set with which the less expensive and more generally used wireless telephone receiving devices are equipped, and therefore at comparatively slight expense the amateur enthusiast is able to equip his receiving set with a loud speaker, which attachment requires no change in his receiving set or purchase of new fittings.

My improved loud speaker is also easily

portable and may be removed from room to room and up and down stairs or otherwise, which would be inconvenient in the case of a phonograph.

Many other advantages will suggest themselves to one familiar with the art of wireless telephony.

What I desire to claim is:—

1. A sound amplifier for the purposes described, consisting of three amplifying chambers arranged in parallelism and comprising a large central chamber expanding toward its emission opening at the front of the instrument and two smaller chambers arranged one at each side of the larger chamber, said smaller chambers expanding rearwardly of the instrument and having their larger ends communicating with the smaller end of the central chamber, and means for introducing the sounds to be amplified at the smaller ends of the side chambers.

2. A sound amplifier for the purposes described, consisting of three amplifying chambers arranged in parallelism and comprising a large central chamber expanding towards its emission opening at the front of the instrument and two smaller chambers arranged one at each side of the larger chamber, said smaller chambers expanding rearwardly of the instrument and having their larger ends communicating with the smaller end of the central chamber, and a pair of tubes within the central chamber having one end connected to the smaller ends of the side chambers and having their other ends connected to the sound transmitting means.

3. A sound amplifier for the purposes described, consisting of three amplifying chambers arranged in parallelism and comprising a large central chamber expanding toward its emission opening at the front of the instrument and two smaller chambers arranged one at each side of the larger chamber, said smaller chambers expanding rearwardly of the instrument and having their larger ends communicating with the smaller end of the central chamber, and a pair of tubes within the central chamber, the forward ends of said tubes being connected to the smaller ends of the side chambers while the rear ends of said tubes connect with ports in the top wall of the central chamber for connection with the sound transmitting means.

4. A sound amplifier for the purposes described, consisting of three amplifying chambers arranged in parallelism and comprising a large central chamber expanding toward its emission opening at the front of the instrument and two smaller chambers arranged one at each side of the larger chamber, said smaller chambers expanding rearwardly of the instrument and having

their larger ends communicating with the smaller end of the central chamber, and a pair of tubes within the central chamber, the forward ends of said tubes being connected to the smaller ends of the side chambers while the rear ends of said tubes connect with ports in the top wall of the cen- tral chamber for connection with the sound transmitting means, said tubes expanding toward their connections with the side chambers. 10

Signed at Pittsburgh, Pa. this 14th day of July, 1922.

JAMES ALBERT PENGRA.
